UNITED STATES PATENT OFFICE.

EMANUEL METZGER, OF NEW YORK, N. Y.

GARMENT.

1,211,954.

Specification of Letters Patent.

Patented Jan. 9, 1917.

Application filed June 5, 1916. Serial No. 101,681.

To all whom it may concern:

Be it known that I, EMANUEL METZGER, a citizen of the United States, and a resident of the borough of Manhattan, city, county, and State of New York, have invented certain new and useful Improvements in Garments, of which the following is a specification.

My invention relates to outer garments for feminine wear, especially those for girls and misses, and more especially to what are known as "sailor" dresses or suits,—the main object being to afford a garment of this class that may be quickly and conveniently transformed or converted in appearance from a regulation sailor suit into a middy-blouse garment, or vice versa, as may be preferred or found most expedient in use.

The invention consists in the specific construction and arrangement of parts described and claimed,—a distinctive feature being the means whereby the dress may be made to assume a one-piece or a two piece garment effect, as hereinafter more fully set forth.

In the accompanying drawings, Figure 1, is a front view of the dress arranged to afford a regulation sailor suit, one piece effect; Fig. 2, is a like view, with parts broken away; Fig. 3, is a front view of the dress arranged to afford a middy-blouse two piece effect; Fig. 4, is a rear view of the garment; Fig. 5, is a detail view showing the front skirt band loosened from the brassière lining.

The back of the garment always remains substantially the same in condition and appearance, as in Fig. 4. To the yoke *y*, is attached the sailor collar *c*, sleeves *s*, *s*, and back plaits *b*, *b'*, Fig. 4. Also to the front of the yoke *y*, is attached the blouse front *f*, the upper side portions of which are also sewed to the sleeves *s*, *s*, and back side plaits *b*', *b*'. A simulated under waist, lining, or brassière front *a*, is attached to the shoulder seams, yoke, and under arm seams, of the garment, its lower edge being provided with a series of buttons *a*', *a*', for detachable engagement with corresponding button holes *c*², *c*², on the skirt waist band *c*', of the front skirt *c*. The sides of the front skirt *c*, are sewed to the side back plaits *b*', *b*', an opening *c*³, being left at the waist on each side to facilitate the donning or removal of the garment,—these openings *c*³, being closed normally by suitable garment fastenings.

The belt *d*, is sewed to and overlaps the upper edge or waist band *c*', of the front skirt *c*, concealing the button holes *c*², *c*², etc. It extends loosely around the back of the garment, the ends being adjustable one over the other by means of suitable garment fastenings, as for instance the buttons *d*', *d*', and button holes *d*², *d*².

The lower side edges of the blouse front *f*, are formed with flaps or extensions *f*', *f*', provided with button holes *f*², *f*², for engagement with buttons *b*'', *b*'' on the side back plaits *b*', *b*', (Fig. 4) when the lower portion of the front *f*, is arranged to extend down over the upper portion of the skirt front *c*, to give the "middy blouse" effect, as in Figs. 3, and 4. When the "regulation sailor suit" effect is desired these flaps or extensions *f*', *f*', are loosened from the buttons *b*'', *b*'', the upper edge of the front skirt is loosened from the buttons *a*', *a*', on the lower edge of the brassière or lining *a*, and the whole lower portion of the blouse front *f*, is positioned back of the front skirt *c*, and behind the front portion of the belt *d*, as shown in Figs. 1, and 2.

Thus my improved garment serves a two-fold purpose, namely, when worn with the lower portion of the blouse front tucked in behind the front skirt the dress appears as an ordinary regulation sailor suit, as in Figs. 1, and 2, the belt apparently being attached to the blouse or having that effect, whereas when the blouse extends down in front of the skirt, as in Figs. 3, and 4, the garment has the appearance of the present day two-piece middy blouse dress,—the belt in the first instance appearing all the way around the garment, while in the latter instance it gives the effect of a belted back only. In either case while the front effect is changed the back of the garment always remains essentially the same in appearance.

What I claim as my invention and desire to secure by Letters Patent is,

1. In a garment of the character designated, the combination with the yoke, back sleeves, etc., of a simulated under waist or brassière, a front skirt the upper edge of which is detachably secured to said under waist or brassière, and a blouse front the lower part of which is adapted to be positioned either in front of or behind the said skirt front.

2. In a garment of the character designated, the combination with the yoke, back,

sleeves, etc., of a simulated under waist or brassière, a front skirt the upper edge of which is detachably secured to said under waist or brassière, a blouse front the lower part of which is adapted to be positioned either in front of or behind the said skirt front, and a belt band secured to the waist band of the skirt front and concealing the means of attachment between the 10 front skirt and waist lining or brassière.

3. In a garment of the character designated, the combination with the yoke, back, sleeves, etc., of a simulated under waist or brassière, a front skirt the upper edge of 15 which is detachably secured to said under waist or brassière, a blouse front the lower part of which is adapted to be positioned either in front of or behind the said skirt front, and a belt band secured to the waist band of the skirt front and concealing the 20 means of attachment between the front skirt and waist lining or brassière, said belt band

extending loosely around the back of the garment and being provided with means for the adjustment of the free ends one upon the 25 other.

4. In a garment of the character designated, the combination with the yoke, back, sleeves, etc., of a simulated under waist or brassière, a front skirt the upper edge of 30 which is detachably secured to said under waist or brassière, and a blouse front the lower part of which is adapted to be positioned either in front of or behind the said skirt front, said blouse front being formed 35 with lateral flaps or extensions at its lower side edges, together with means for detachably securing said lateral flaps or extensions to back portions of the garment.

EMANUEL METZGER.
